CHILD'S FOOT PROPELLED VEHICLE

Cecil Arthur Rassier, Erith, England, assignor to
D. Sebel & Company Limited, Erith, England

Filed Apr. 2, 1958, Ser. No. 50,312

Term of patent 14 years

(Cl. D34—15)

FIG.1

FIG.2

FIG.3

Figure 1 is an overhead three-quarter front perspective view of a child's foot propelled vehicle showing my new design, the other side having substantially the same appearance;

Figure 2 is an underneath three-quarter rear perspective view thereof; and

Figure 3 is a side perspective view thereof.

I claim:

The ornamental design for a child's foot propelled vehicle, as shown and described.
